DESIGN FOR A HAND BAG

Rudolph Lobel, Brooklyn, N. Y.

Application December 22, 1932. Serial No. 46,561

Term of patent 3½ years

To all whom it may concern:

Be it known that I, RUDOLPH LOBEL, a citizen of the United States residing at borough of Brooklyn, city of New York, in the county of Kings and State of New York, have invented a new, original, and ornamental Design for a Hand Bag, of which the following is a specification reference being had to the accompanying drawing, forming part thereof.

Fig. 1 is a front face view of a hand bag showing my new design.

Fig. 2 is a similar view, showing the said hand bag open.

Fig. 3 is a rear view of Fig. 1.

Fig. 4 is a side elevational view of Fig. 2.

The dominant feature of my design is the arrangement of a circular member on the flap of the hand bag, opposed decorative configurations on the horizontal center line of said circular member, a vertical slot or stripe on the front of the hand bag below the flap and in line with said circular member, and a circular member on the front of the hand bag associated with said stripe by reason of being engaged over a portion thereof.

I claim:

The ornamental design for a hand bag, as shown and described.

In testimony whereof I have affixed my signature this 19th day of December, 1932.

RUDOLPH LOBEL.
